UNITED STATES PATENT OFFICE

GEORGE H. TABER, OF ELMIRA HEIGHTS, NEW YORK

POWER ACTUATED SHOCK ABSORBER

Application filed December 24, 1928. Serial No. 328,284

The present invention relates to a power actuated shock absorber and an object of the invention is to provide means for increasing the speed of movement between the wheel and the vehicle body when the wheel is given an impetus to move in one direction either by a bump or a depression. Another object of the invention is to utilize a moving part on the vehicle for increasing the speed of movement of the wheel with reference to the vehicle body when the latter is given an impetus to move in one direction by striking a bump or hollow. Still another object of the invention is to establish grip relation with a rotating part when the wheel is given an impetus to move either up or down by a bump or a hollow for the purpose of increasing the movement of the wheel in the direction to which the impetus is given by the bump or hollow. A further object of the invention is to provide two gripping devices mounted on the running gear and cooperating with a wheel, one of said gripping devices being operated to move the wheel toward the vehicle frame or lift the same at an increased speed when the wheel strikes a bump and the other of said gripping devices acting to lower the wheel or move it away from the vehicle frame to cause the wheel to follow the road when the wheel meets a depression. A still further object of the invention is to provide means for retarding or snubbing the return movement of the wheel to normal or neutral position with reference to the vehicle frame. A still further object of the invention is to provide a snubbing means in which the two snubbing elements are normally out of cooperation so that, when moved into cooperation, the moving element will engage the other element without producing any chattering noises. Still another and further object of the invention is to provide a gripping means which speeds up the movement of the vehicle wheel with reference to the vehicle frame on the striking of a bump or depression constructed so as to limit the gripping action so that an excessive gripping action on the wheel will not be obtained.

To these and other ends, the invention consists of certain parts and combinations of

parts all of which will be hereinafter described: the novel features being pointed out in the appended claims.

In the drawings:

Fig. 1 is a side view of a front wheel of a vehicle with fragments of the vehicle frame in section equipped with one embodiment of the present invention;

Fig. 2 is an enlarged front view showing the shock absorber in position, parts being shown in section;

Figs. 3 and 4 are fragmentary views partially in section showing the manner in which the gripping members are supported;

Fig. 5 is an enlarged fragmentary section through one of the gripping means;

Fig. 6 is a detail view of the two gripping rings side by side;

Figs. 7 and 8 are detail views of the detent and the bell crank lever by which it is carried;

Fig. 9 is another detail view of the detent;

Fig. 10 is a side view of the shock absorber with parts broken away; and

Fig. 11 is a fragmentary view showing the parts for actuating the frictional bands.

Fig. 12 is a detail view of the shock absorber.

The present invention contemplates a shock absorber in which the impetus imparted to the wheel by striking a bump or falling into a depression is increased in such a manner that the shock imparted to the wheel is substantially absorbed before it reaches the vehicle body. In other words, when the wheel strikes a bump, it is, due to the speed of the car, substantially lifted over the bump, whereas, when the wheel strikes a hollow, it is projected into the hollow so that the vehicle frame substantially maintains the plane in which it is traveling. The invention utilizes a gripping means which is normally out of contact with a moving part, such as a friction drum on the wheel of the vehicle, and which is brought into engagement with the moving part immediately impetus is imparted to the vehicle wheel by an elevation or depression in the roadway for causing the wheel to advance in the direction in which it is moved by the bump or depression. Pro-

90

95

100

vision is also made for releasing the gripping means immediately that the movement is completed and for retarding the return movement of the wheel to its normal running position with reference to the vehicle frame. In the illustrated embodiment, two distinct gripping devices with two distinct thrust connections with the vehicle frame are employed. These two gripping devices operate in opposite directions so as to exert forces in two opposite directions, and the thrust connections between these two gripping devices and the frame connect with the gripping devices, one in front of the vehicle axle and the other in rear of the vehicle axle, the one in front becoming effective when a bump or elevation gives impetus to the vehicle wheel and the one in the rear becoming effective when a depression or hollow gives impetus to the vehicle wheel. The construction of the two gripping mechanisms are identical except for their reverse positions, so that it will be necessary to describe only one of them.

Referring more particularly to the illustrated embodiment of the invention, 1 indicates a portion of the frame of the vehicle which is supported by springs (not shown) by the axles 2. Preferably on each of four wheels 3 of the vehicle, only one being shown, is arranged, as is common, a brake drum 4 forming a rotating part, the interior surfaces of which cooperate with a brake band 5 forming part of the common brake mechanism of the car. Surrounding each brake drum 4 and spaced therefrom but concentric therewith is a friction drum 6 which is rigidly secured to the axle 2. Arranged between the outer face of the usual brake drum 4 and the inner face of the friction drum 6 is a gripping means, in this instance, in the form of a split ring or band 7. This band is covered or faced on its inner and outer perimeter with strips 8 and 9 of material which has high friction qualities and it is supported in such a manner that the brake drum 4 turns relatively thereto. For holding the means in a neutral position, two spring arms 10 may be provided which have at their free ends projections 11 engaging in pockets in holding pieces 12 mounted on the drum 6 which project into slots 13 formed in opposite sides of the split bands at the top and bottom thereof or in any other places that may be required. These centering pieces 12 normally tend to hold the surfaces 8 and 9 out of contact with the outer periphery of the drum 4 and the inner periphery of the drum 6. This is the neutral position of the split band 7 in a normal riding of the vehicle.

With the end in view of providing a shifting motion or swinging motion of the split band 7, such band may have a boss 14 secured thereto at 15 to which an arm 16 is bolted at 17. This arm has a laterally projecting pin 18 projected therefrom and provided

with a ball or pivot 19 at its outer end on the inner side of the drum 6. This ball fits in a socket bearing 20 in the lower end of a thrust rod 21, the latter having a socket bearing 22 at its upper end receiving a ball 23 on the end of a pin 24 which is bolted at 25 to the frame 1. It will be seen that by this construction, when there is any relative movement between the axle 2 and the frame 1, the band 7 will be shifted or turned about the axis of turning of the wheel and relatively to the friction drum 6. Extending from the ball 23, in line with the axis of the pin 24, is another pin 18^a which carries a ball 18^b similar to the pivot 23. This pivot is provided for the thrust rod 21 projecting from the impetus imparting device which gives the axle a thrust in the opposite direction.

In order that with such turning of the friction band 7 the friction band may be expanded and contracted, the end of the band 7 may be provided with two perforated lugs 26 and 27 which are projected through a slot or opening 28 in the friction drum 6 and which are connected by a rod 29. This rod is surrounded by a helical spring 30 seating in cup washers 31 at its opposite ends, the washers resting against the opposed spaces of the perforated lugs 26 and 27. This rod may have one end screw threaded at 32 for engagement by an adjusting nut 33 which bears against the perforated lug 26. The other end of this rod is pivoted at 34 to a bell crank lever 35, the latter being pivoted at 36 to an arm 37 projected from the outer face of the perforated lug 27. Pivoted at 38 is a swinging pawl 39 provided with a stop 40 adapted to cooperate with a stop 41 on the bell crank lever 35, the two stops normally being held in engagement by a spring 42. This pawl member is considerably wider than the slot or opening 28 in the drum 6 so that it may cooperate at its ends with two cams 41^a bolted at 42^a on opposite sides of the slot 28 to equalize a thrust on the pivot 38 on the pawl or dog 39. The cams 41^a are so constructed and arranged that when the band 7 is in its neutral position, the pawl 39 rests against the surface 43. Connecting with the portion 43 is the portion 44 which tends to shift the bell crank lever 35 on its pivot 36 when the band 7 is shifted in a direction to carry the pawl 39 off the neutral portion 43 onto the portion 44. Connecting with the portion 44 is a portion 45 which is concentric with the axis of turning of the wheel and which is engaged by the pawl 39 after it has been shifted on its pivot by the portion 44 of the cam in order to hold the position of the pawl notwithstanding a continued movement of the band 7. When the bell crank lever 35 shifts it tends to draw the two ends of the split band 7 together and thus contract the band 7 upon the outer face of the drum 4 which is turning with the wheel. This oc-

5 curs whenever there is a tendency for the vehicle body and the axle to approach each other. The maximum amount or limit of this friction may be determined by the adjustment of the nut 33 on the screw 32 but it will be understood that between the two limits, that is the neutral position and the position of the pawl on the portion 43, the amount of friction will be variable in proportion to the movement of the frame toward the axle. After the portion 43 is reached by the pawl 39, the maximum friction of the band 7 on the drum 4 is obtained, and, notwithstanding the further movement of the vehicle frame with reference to the axle housing, the friction on the drum 4 is not increased. When the vehicle frame and the axle separate or move away from each other or a reversal of the movement takes place, the pawl 39 swings 10 so as to carry the stop 40 away from the stop 41 and permits the spring 30 to act in order to separate the ends of the band 7 and also permit the band to expand, thus throwing the surface 8 into engagement with the inner 15 face of the housing or drum 6. It will be understood that during the ordinary travel of the vehicle, the frame and the axles are constantly moving toward and from each other. With each movement toward each 20 other, the pawl will cooperate with the cam 41 and cause the split band 7 to bind against the drum 4 and with each movement away from each other the bands 7 will expand and cooperate with the housing or drum 6. The 25 pawl, when the frame and the axle are in neutral position rests upon the cam 43, or in other words, in the normal running of the vehicle the pawl rides on the portion 43. A housing 46 encloses the expanding and contracting mechanism being held in place by screws 47 which anchor in the friction drum 6.

30 It is apparent that the drum 4 forms a part turning continuously during the running of the vehicle. When this part is gripped in rear of its turning axis due to the wheel entering a depression or hollow, the drum tends to lift the thrust rod 21 in rear of the turning axis and in this way to effect the movement of the frame and the 35 wheel away from each other, causing the wheel to advance quickly into the depression. On the return movement a snubbing or retardation takes place due to the gripping of the drum 6 on the axle by the band 7.

40 When a bump or elevation is struck by a wheel, the gripping device operated by the thrust rod 21 in front of the axle becomes effective and the wheel and the vehicle frame are by the drum 4 drawn together thus tending to lift the wheel over the bump or elevation. In other words, a bump or depression imparts to the wheel an impetus in one direction and this action is utilized to increase the speed of movement between the

45 parts in the direction in which the impetus is given.

50 While, in this instance, two gripping devices are employed for increasing the movement of the wheel with reference to the frame, one in one direction and the other in the opposite, it is apparent that only one may be employed, either for moving the wheel toward the vehicle when bumps are met with or moving the wheel away from the vehicle when depressions are encountered.

55 What I claim as my invention and desire to secure by Letters Patent is:

1. The combination with an axle, a frame supported to move toward and from the axle, and a wheel arranged to move with the axle toward and from the frame, of means for effecting an increased speed of movement between the frame and the axle when the axle is given an impetus to move in one direction from a normal position.

60 2. The combination with an axle, a frame supported to move toward and from the axle, and a wheel arranged to move with the axle toward and from the frame, of means for effecting an increased speed of movement between the frame and the axle when the axle is given an impetus to move in one direction from a normal position, and means retarding the relative movement in the other direction.

65 3. The combination with an axle, a frame supported to move toward and from the axle, and a wheel arranged to move toward and from the frame with the axle, of a rotating part carried with the axle and movable with the latter relatively to the frame, and means for gripping said rotating part, said means having connection with the frame to cause the rotating part to effect relative movement between the axle and the frame.

70 4. The combination with an axle, a frame supported to move toward and from the axle, and a wheel arranged to move toward and from the frame with the axle, of a rotating part carried by the axle and movable with the latter relatively to the frame, a band arranged to cooperate with the rotating part to grip the same, means for connecting said band with the frame so that the band is turned about the rotating part upon the relative movement between the axle and the frame, and means for automatically causing the band to grip the rotating part upon such turning movement in one direction so that the rotating part speeds up the movement between the axle and the frame.

75 5. The combination with an axle, a frame supported to move toward and from the axle, and a wheel arranged to move toward and from the frame with the axle, of a rotating part carried by the axle and movable with the latter relatively to the frame, a band arranged to cooperate with the rotat-

ing part to grip the same, means for connecting said band with the frame so that the band is turned about the rotating part upon the relative movement between the axle and the frame, and means for automatically causing the band to grip the rotating part upon such turning movement in one direction so that the rotating part speeds up the movement between the axle and the frame, said means having provision for automatically releasing said gripping engagement of the band with the rotating part upon the relative movement of the axle and the frame in the opposite direction.

6. The combination with an axle, a frame supported to move toward and from the axle and a wheel arranged to move toward and from the frame with the axle of a rotating part carried by the axle and movable with the latter relatively with the frame, of a split band arranged to cooperate with the rotating part to grip the same, means connecting the split band with the frame to cause the turning of the split band about the rotating part upon the relative movement between the axle and the frame, and means connecting the ends of the split band to cause them to grip the rotating part upon the turning of the split band.

7. The combination with an axle, a frame supported to move toward and from the axle and a wheel arranged to move toward and from the frame with the axle of a rotating part carried by the axle and movable with the latter relatively with the frame, of a split band arranged to cooperate with the rotating part to grip the same, means connecting the split band with the frame to cause the turning of the split band about the rotating part upon the relative movement between the axle and the frame, and means connecting the ends of the split band to cause them to grip the rotating part upon the turning of the split band, said means comprising a movable member connected to one end of the split band and having connection with the other end of the split band to effect movement between the ends upon the movement of said member, and a device arranged to shift said movable member upon the turning of the split band.

8. The combination with an axle, a frame supported to move toward and from the axle and a wheel arranged to move toward and from the frame with the axle of a rotating part carried by the axle and movable with the latter relatively with the frame, of a split band arranged to cooperate with the rotating part to grip the same, means connecting the split band with the frame to cause the turning of the split band about the rotating part upon the relative movement between the axle and the frame, and means connecting the ends of the split band to cause them

to grip the rotating part upon the turning of the split band, said means comprising a movable member connected at one end to the split band and having connection to the other end of the split band so that upon its movement the split band is caused to grip the rotating member, a pawl movably mounted on said movable member, and a cam arranged to engage said pawl to shift the movable member to cause the gripping action when the split band is moved in one direction and to release said movable member to permit the split band to disengage with the rotating part when the split band is moved in the other direction.

9. The combination with an axle, a frame supported to move toward and from the axle and a wheel arranged to move toward and from the frame with the axle of a rotating part carried by the axle and movable with the latter relatively with the frame, a split band arranged to cooperate with the rotating part to grip the same, means connecting the split band with the frame to cause the turning of the split band about the rotating part upon the relative movement between the axle and the frame, and means connecting the ends of the split band to cause them to grip the rotating part upon the turning of the split band, an adjustable rod connecting the ends of the split band and slidable in one of said ends, a bell crank lever pivotally supported on said last mentioned split end and connected with the slidably adjustable rod, a pawl mounted on the bell crank lever, and a cam arranged to engage the pawl when the split ring is moved in one direction to cause the split ring to grip the rotating part, said pawl being movable to effect the release of the rotating part by the gripping means when the gripping member is moved in the opposite direction.

10. The combination with an axle, a frame supported to move toward and from the axle, and a wheel arranged to move with the axle toward and from the frame, of means for effecting the increased speed of movement between the frame and the axle when the axle is given an impetus to move toward the frame from normal position and also away from the frame from normal position.

11. The combination with an axle, a frame supported to move toward and from the axle, and a wheel arranged to move with the axle toward and from the frame, of a rotating part carried with the axle and movable with the latter relatively with the frame, two gripping devices arranged to engage said rotating part, and two connections between the frame and the gripping devices, one with each gripping device, the connection with the two gripping devices being on opposite sides of the axis of turning of the rotary part.

12. In a shock absorber, the combination with a rotating part, gripping means for en-

gaging the rotating part, and a thrust member connected to the gripping means and adapted for connection with the frame of the vehicle.

5 13. The combination with an axle, and a frame supported by the axle to move toward and from the axle, of a rotating part on the axle, gripping means normally out of engagement with the rotating part, and thrust means connecting the gripping means with the frame to effect the gripping action on relative movement between the frame and the axle.

14. The combination with an axle, a spindle supported by the axle, a wheel mounted on the spindle, and a frame supported by the axle and movable toward and from the latter, of a part rotatable with the wheel, gripping means normally out of engagement 70 with such rotary part, and thrust means connected to the frame directly above the axle and with the gripping means to effect the gripping action upon relative movement between the frame and the axle.

15. The combination with an axle, and a frame supported by the axle and movable toward and from the same, a rotary part supported by the axle, gripping means normally out of gripping relation with the rotary part, and a thrust member having a ball and socket connection with the gripping means and a ball and socket connection with the frame.

16. The combination with an axle, a frame supported to move toward and from the axle, and a wheel arranged to move with the axle toward and from the frame, of a part turning with the wheel about the axis of turning of the wheel, a thrust member connected to the frame, and means for connecting said thrust member to the rotating part in rear of the axis of turning of the wheel to cause the wheel to move away from the frame.

17. The combination with an axle, a frame supported to move toward and from the axle, and a wheel arranged to move with the axle toward and from the frame, of a part turning with the wheel about the axis of turning of the wheel, a thrust member connected to the frame, means for connecting said thrust member to the rotating part in rear of the axis of turning of the wheel to cause the wheel to move away from the frame, a second thrust member connected to the frame, and means for connecting said second thrust member to the rotating part in front of the axis of turning of the wheel to cause the wheel to move toward the frame.

18. The combination with an axle, a frame supported to move toward and from the axle, and a wheel arranged to move with the axle toward and from the frame, of a part turning with the wheel about the axis of turning of the wheel, a thrust member connected to the frame, means for connecting said thrust

member to the rotating part in front of the wheel to cause the wheel to move toward the frame.

19. The combination with an axle, a frame supported by the axle to move toward and from the axle, a rotating part on the axle, gripping means arranged about the rotating part and normally out of engagement therewith, said gripping means being rotatable about the rotating part, a thrust member 75 connected with said gripping means and also with the frame, and means for effecting a gripping action on the rotating part when the gripping member is turned in one direction and the release of the rotating part by the gripping means when the latter is turned in the other direction.

20. The combination with an axle, and a frame supported by the axle to move toward and from the axle, of a rotating part on the axle, gripping means arranged about the rotating part and normally out of engagement 80 therewith, said gripping means being rotatable about the rotating part, a thrust member connected with said gripping means and also with the frame, means for effecting a gripping action on the rotating part when the gripping member is turned in one direction and the release of the rotating part by the gripping means when the latter is turned in the other direction, and a fixed part carried by the axle and with which the gripping means engages to effect a retarding of the movement of the frame relatively to the axle 85 when the gripping means is turned in the direction to release the rotating part.

21. The combination with a rotating part and a fixed part, of gripping means normally out of engagement with both parts, and a thrust member connected with the gripping 90 means and adapted for connection with the frame of the vehicle so that upon the movement of the frame in one direction with reference to the rotating and the fixed part, the rotating part will be engaged, and, upon the movement of the frame in the other direction, the fixed part will be engaged by the gripping member.

22. A shock absorber comprising two parts having opposed concentric cylindrical surfaces arranged in spaced relation, one part rotating and the other being fixed, a split 105 expandible and contractible ring arranged between the parts, and means causing said ring to grip the rotating part to absorb the shock, and to grip the fixed part to produce a retarding action.

23. A shock absorber comprising two parts having opposed concentric cylindrical surfaces arranged in spaced relation, one part rotating and the other being fixed, a split 110 expandible and contractible ring arranged between the parts, means causing said ring to grip the rotating part to absorb the shock, and to grip the fixed part to produce a retarding action.

tarding action, and yielding means normally supporting said split ring out of engagement with both cylindrical surfaces.

24. In a vehicle of the type having a chassis comprising a frame, a running gear resiliently supporting the frame, and a traction wheel turning on the running gear, distinguished by means for shifting the wheel and the adjacent portion of the running gear relatively to the frame in a direction in which an impetus is given to the wheel.

25. In a vehicle, the combination with a chassis frame, an axle, and a traction wheel supported by the axle, of means for shifting the wheel and the adjacent portion of the axle toward the frame when the wheel is given an impetus toward the frame and away from the frame where the wheel is given an impetus to move away from the frame.

26. In a vehicle, the combination with a running gear, and a frame resiliently supported by the running gear, of a traction wheel turning on the running gear, of means for shifting the wheel and the adjacent portion of the running gear in one direction relatively to the frame when the wheel is given an impetus to move in such direction, and means for retarding the return movement of the wheel with reference to the adjacent portion of the running gear.
